Arthur Little Tobin

UNITED STATES PATENT OFFICE

ARTHUR LITTLE TOBIN, OF SALEM, MASSACHUSETTS, ASSIGNOR TO RUGGLES-
KLINGEMANN MFG. CO., OF SALEM, MASSACHUSETTS

THROTTLING VALVE

Application filed November 12, 1927. Serial No. 232,797.

This invention relates to throttling valves of the type generally used in connection with regulators for controlling speed of fan engines to maintain uniform boiler pressure. 5 The object of the invention is to keep the main valve in a regulating position by automatically opening the by-pass when the main valve is near its open position, thereby supplying the additional steam required to drive the main valve back into a regulating position, leaving the by-pass open until such time as the main valve is near its closed position, and then automatically closing the by-pass and again driving the main valve back 15 into a regulating position.

It will be understood that when fan engine throttling valves are connected to regulators of the servo motor or other type commonly used to control boiler operation, that the throttling valve must be of a size which will supply the necessary amount of steam for any possible peak load condition. If the valve is of a sufficient size to supply the necessary steam to the fan engine to maintain say 200% boiler rating then it will be too large when boilers are operated at normal rating of say 100%. Where the valve is too large for the requirements, the regulator becomes an off and on affair, resulting in the fan engine being slowed down to idling speed half of the time, and the other half, producing a speed of the fan much too great for the requirements. The remedy is in using a smaller valve, but with the smaller valve no means is provided for automatically taking care of the peak load condition. My invention meets the requirements of a satisfactory throttling valve for normal condition and one which will automatically adjust itself to take care of an extreme condition.

Referring to the drawing Fig. 1 shows a vertical section through the valve casing showing the arrangement of main and by-pass valves. Fig. 2 shows an exterior vertical elevation of the valve and the arrangement of its operating levers.

Referring to Fig. 1, (1) represents the valve casing; (2) the main valve; (3) the by-pass valve; (4) is the port through the main

valve; and (5) is the port through the by-pass valve.

Referring to Fig. 2, (6) is the operating lever which controls the operation of main valve (2); and (7) is the by-pass valve arm. 55

It will be understood that both the main and by-pass valves have stems which extend through stuffing boxes and connect to the outside operating member (6) and (7) in such a manner as to be operated thereby. A 60 crank pin (8) is secured to the end of arm (7) and has a roll (9) which enters a slot (10) in the lever (6). As shown in the drawing the valve is in a closed position, both ports (4) and (5) being closed. If the lever (6) should be moved to the left it will rotate and open the main valve (2) so steam will pass from either end of the valve, which ever is used as the inlet, to the outlet of the valve. It will be seen that the opening of 70 the main valve will not disturb the position of the arm (7), the by-pass valve (3) remaining closed until the main valve (2) is opened to a point where the opposite end of the slot (10) engages the roll (9) and then 75 both valves will be rotated and moved to their open position.

Should the main valve then be moved toward its closed position the by-pass valve will remain open until the main valve has reached 80 to nearly its closed position when the roll (9) will be again engaged and both valves moved to a closed position as shown in the drawing.

It will be seen that the by-pass valve has a shorter operating arm than the main valve 85 and therefore, a much quicker motion. The travel of the by-pass is also much less between open and closed positions than that of the main valve. This means that the main valve can be operated to approximately three-fourths closed before starting to close the by-pass, and likewise operated to three-fourths open before starting to open the by-pass, both valves completing their final opening or closing movement simultaneously. 90

I claim:

1. In a throttling valve comprising a valve casing having an inlet and an outlet for the passage of pressure fluid, a main valve and a by-pass valve in said casing, an actuating 100

member for operating the main valve and means whereby said actuating member operates the by-pass valve at near the open and closed positions of the main valve only to thereby further increase and decrease the flow of pressure fluid through said casing.

2. In a throttling valve comprising a valve casing, a main valve and a by-pass valve in said casing, an actuating member for operating the main valve uniformly between its open and closed positions, and means whereby said actuating member operates the by-pass valve intermittently at near the open and closed positions of the main valve only to thereby further increase and decrease the flow of pressure fluid through said casing.

3. In a throttling valve comprising a valve casing, a main valve and a by-pass valve in said casing, an actuating member for operating the main valve, said actuating member also operating the by-pass valve, but with a lost motion to allow the by-pass to remain closed until the main valve is nearly open, and likewise, to allow the by-pass to remain open until the main valve is nearly closed the arrangement being such as to further increase and decrease the capacity of said valve.

4. In a throttling valve comprising a valve casing having an inlet and an outlet for the passage of pressure fluid, a main valve and a by-pass valve in said casing both valves being arranged to retard the flow of pressure fluid from the inlet to the outlet of said casing, means to operate the main valve between its open and closed positions to increase and decrease the flow of fluid through said casing, said means also operating the by-pass valve near the open and closed positions of the main valve only, to thereby further increase and decrease the flow of pressure fluid through said casing.

5. In a steam throttle valve, the combination of a valve casing having an inlet and an outlet, a main valve in said casing and means to operate the main valve to control the flow of steam from the inlet to the outlet, a by-pass valve located in a passage extending around the main valve from the inlet to the outlet, the arrangement being such that the main valve operating means, also controls the operation of the by-pass valve near the open and closed positions of the main valve only, to thereby further increase and decrease the flow of steam through said valve casing.

6. In a steam throttle valve, the combination of a valve casing having an inlet and an outlet, a main valve in said casing, means to operate the main valve to control the flow of steam from the inlet to the outlet, a by-pass valve located in a passage extending around the main valve from the inlet to the outlet operating means for said by-pass valve, a lost motion connection between the operating means of the main valve and the operating means of the by-pass valve, the arrangement

being such that the main valve operating means also controls the operation of the by-pass valve at near the open and closed positions of the main valve only, to thereby further increase and decrease the flow of steam through said valve casing.
